UNITED STATES PATENT OFFICE

HERMAN R. BERTRAM AND CARL L. FRITZ, OF KANSAS CITY, MISSOURI

GLOVE INFLATER

Application filed April 2, 1931. Serial No. 527,318.

This invention relates to inflating devices and more particularly to glove inflators for distending the body and fingers of a glove after the same has been cleaned to permit the glove to dry in distended position.

The principal objects of the invention are to provide convenient means for controlling delivery of air under pressure into a glove mounted on an inflater for reducing the labor and time necessary to properly shape the glove.

Other objects of the invention will be apparent in the course of the following description of one form of a glove inflater embodying the invention and illustrated in the accompanying drawing, wherein:

Fig. 1 is a perspective view of a glove inflater constructed in accordance with the invention, an air supply pipe and operating pedal being shown fragmentarily.

Fig. 2 is a longitudinal vertical section through the device on the line 2—2, Fig. 3.

Fig. 3 is a section on the line 3—3, Fig. 2.

Referring in detail to the drawing:

25 4 designates a hollow tubular casing or nozzle member considerably elongated to provide relatively extensive inlet and outlet portions 6 and 8 having chambers 10 and 12 of substantial volume and communicating through a valved port as later described. The outlet end is flattened and has substantial width and is formed to fit snugly within the wrist of a glove as shown in Fig. 1. The nozzle is preferably elongated in 30 cross section and is thus adapted to fit the wrist of a glove.

A reduced nipple portion 14 on the inlet end of the nozzle is connected to a line 16 leading from a compressor or other means 40 for supplying air under pressure (not shown), whereby the inlet chamber 10 of the nozzle is in constant communication with the source of supply, and air is always present under pressure in said chamber.

45 The inlet portion of the nozzle member is provided with lateral bracket wings 18 having apertures to receive bolts for fixing the device to the top of a table so that the outlet end may project from the edge of the 50 table.

Formed in the middle portion of the nozzle in front of the wings 18 is a valve body element including a partition 20 having a horizontal wall portion 22 slightly above the horizontal middle plane of the nozzle 55 channel and provided with a port 23 forming a beveled seat for a valve 24 operating below the wall 22.

The valve includes a spider-like upper guide portion 25 for centering the valve on the port, and an integral stem 26 projecting into a recess 28 formed in a plug 30 threaded into an opening 32 in the lower wall of the nozzle. A coil spring 34 yieldingly holds the valve against the port seat.

55 A valve-operating rod or stem 36 movable in an opening 38 in the upper wall of the nozzle bears against the valve spider and is guided in an elongated externally threaded sleeve 40 threadedly mounted in the opening 70 38. The sleeve affords means for mounting stem packing and stem operating elements on the nozzle as presently described.

60 Threaded on the sleeve is a nut 42 seated on a boss 44 formed on the upper side of the 75 nozzle, and the apertured horizontal arm 46 of a yoke 48 is freely movable over the sleeve to rest on the nut and provided with ears 50 at the upper end of the vertical portion of the yoke, apertured to support a pivot pin 80 52 and spaced to accommodate the enlarged end 54 of a lever 56 mounted on the pin. A nut 58 is threaded on the sleeve to retain the yoke on the nozzle, and a guide cap or gland 85 60 threaded on the top of the sleeve retains packing 62 in engagement with the stem.

85 The lever extends transversely of the nozzle over the path of the stem 36 and when depressed will engage the stem to urge the same against the valve. A link 64 pivoted 90 in the outer end of the lever is pivotally connected to a pedal lever 66 having a mounting on the floor beneath the nozzle.

95 Depression of the pedal will depress the lever against the stem and move the stem and valve against the influence of the spring to permit air under pressure in the nozzle and supplied from a source not shown, to pass through the partition port into the outlet end of the nozzle.

When the pedal is released, the spring 34 will move the valve to close the port, and incidentally push the stem 36 against the lever 56 to elevate the same and retract the pedal.

- 5 In order to limit upward pivotal movement of the lever 56, a depending tongue 68 is formed on the end 54 of the lever and swings into engagement with the edge of the wall portion 70 of the yoke at the bottom of the spacing slot between the ears 50, when the lever has been retracted sufficiently to permit the valve to close the port.

- 10 In using the device, a glove may be mounted on the outlet end of the nozzle and retained by hand while the operator presses the pedal to admit air into the chamber 12 to pass into the glove for distending the glove.

- 15 When the pedal is released the spring in 20 the nozzle will move the valve to close the port. A substantial amount of air will be retained in the nozzle portions to prevent sudden and complete exhaustion of air pressure and thus tend to maintain necessary pressure to remove the wrinkles from the glove to restore its shape and size.

- 25 A substantial volume of air will be retained under pressure in the large chamber 10, and air under pressure may move rapidly through 30 the relatively large port when the valve is opened into the outlet chamber. The air in the outlet chamber is thus quickly put under pressure, and the outlet chamber is sufficiently long and has sufficient cross sectional area 35 to prevent rush of thin jets of air into the glove.

- The inlet chamber 10 may be of any desired shape, but in any event will have substantially greater volume than an equal 40 length of the supply pipe. The outlet chamber preferably has substantially the same volume as the inlet chamber.

What we claim and desire to secure by Letters Patent is:

- 45 A glove inflator including a nozzle having an open end rectangular in cross section and curved at its edges to receive and shape the wrist portion of a glove thereover and support the glove thereon, a partition in said nozzle forming inner and outer chambers therein and provided with a valve port, an air supply line connected with the inner chamber, a valve spring-pressed to close said port in the direction of flow of air through the nozzle, a thrust rod engageable with the valve, a yoke mounted on the nozzle, and a lever on the yoke engageable with the thrust rod to open the valve.

- 50 In testimony whereof we affix our signatures.

HERMAN R. BERTRAM.
CARL L. FRITZ.
